UNITED STATES PATENT OFFICE.

WALTER EVERETT MOLINS, OF DEPTFORD, LONDON, ENGLAND.

PACKING MACHINERY.

Application filed February 3, 1927, Serial No. 165,702, and in Great Britain February 3, 1926.

This invention is for improvements in or relating to packing machinery and more particularly to packing machinery of the type wherein packets are automatically moved in succession for example, through a vertical stacker from which they have to be removed to be inserted in an outer carton.

The present invention consists of a device for use on a packing machine of the type referred to which comprises means (for example a pusher piece) operable automatically to remove packets in batches from the stacker and deliver the batches alternately to opposite sides of the stacker.

Further, the present invention consists of a device for use on a packing machine of the type referred to which comprises means (for example a pusher piece) operable automatically to remove packets in batches from the stacker so as to deliver the batches alternately to opposite sides of the stacker and means operable automatically to detect whether each batch comprises a predetermined number of packets.

Again the present invention consists of a device for use on a packing machine of the type referred to which comprises in combination means operable automatically to receive packets in line and move the same through a vertical stacker in superimposed relationship, and means (for example a pusher piece) operable automatically to arrange the packets in batches and move the same in succession in a horizontal plane.

Further, the present invention consists of a device as set forth in the preceding paragraph, wherein means are provided to detect automatically whether each batch comprises a predetermined number of packets.

The invention will be hereinafter more particularly described with reference to the accompanying drawings, in which:—

Fig. 1 illustrates in elevation a device constructed according to the present invention.

Fig. 2 is a plan view of Fig. 1.

Fig. 3 is an enlarged plan view of the diamond threaded screw, pusher piece and cam bar of the device illustrated in Fig. 1.

Fig. 4 is a side elevation of Fig. 3.

Figs. 5, 6 and 7 are detailed views of the tracer which engages with the diamond threaded rod.

Fig. 8 is a side elevation of a slipping clutch mechanism and

Fig. 9 is a detailed elevation of the cam bar.

Referring to the drawings, a packet of cigarettes is enveloped, for example, in an outer covering of thin transparent paper, by a machine constructed according to British 60 specifications Nos. 165,891, 214,792 and 255,937, and the successive packets so enveloped are automatically moved in line along a bed 1 of the wrapping machine into position above an upwardly movable platform 2 65 which moves each successive packet into a vertical stacker 3. The packets of cigarettes are moved intermittently through the stacker until they extend one above the other beyond the delivery end thereof.

Mounted on either side of the delivery end of the stacker 3 is a platform 4 provided, at the end adjacent to the delivery end of the stacker, with a sloping portion 5, the purpose of which will be hereinafter described. 75 Arranged to move over the platforms 4 is a pusher piece 6 which is carried by a bracket 7 threaded upon a diamond threaded rod 8 upon which is mounted a pinion 9 driven by a pinion 10 secured to a continuously rotated 80 shaft 11 through a slipping clutch mechanism. The pusher piece 6 is secured to a spindle 12 slidable in the bracket 7 the pusher being guided between guide rollers 13. The lower end of the spindle 12 carries a 85 roller 14 which is adapted to ride over a cam bar 15.

Pivotedly secured to the cam bar 15 is a link 16 which carries a dog 17 arranged to be moved into engagement with teeth 18 secured to the rod 8. The dog 17 is normally held out of engagement with the teeth 18 by means of a spring 19.

The cam bar 15 which supports the spindle 12, is shaped so that as the pusher piece moves across the delivery end of the stacker 3, the spindle is free to move downwardly so that the lower end of the pusher piece 6 moves in a direction corresponding to the sloping portions 5 of the platforms 4 and is thereafter free to move downwardly still further so as to permit a cam face 20 formed on the side face of the spindle 12 to engage with a cam face 21 formed on the inner face of the link 16 to rock the same about its pivot and thereby move the dog 17 against the influence of the spring 19 into engagement with one of the teeth 18, and arrest the movement of the diamond threaded rod 8. If, however, a predetermined number of 105 packets are located above the delivery end of the stacker 3, the uppermost packet will en-

gage with a horizontal limb 22 of an adjustable bracket 23 secured to the pusher piece 6 and prevent the downward movement of the spindle 12 and thereby enable the pusher piece 6 to move a predetermined number of packets to one side of the delivery end of the stacker. If the desired number of packets are not located above the delivery end of the stacker, the spindle 12 will be free to fall and stop the rotation of the diamond threaded rod 8 in the manner hereinbefore described. The packets, however, continue to be delivered into the stacker 3 and as the packets are delivered above the delivery end of the stacker 3, the leading packet will engage with horizontal limb 22 of the bracket 23 and raise the spindle 12 until the cam 20 disengages with the cam surface 21 on the link 16, whereupon the dog 17 will be released, and the diamond threaded rod permitted to rotate and cause the pusher piece 6 to move the desired number of packets to one side of the delivery end of the stacker.

The bracket 7 which carries the pusher piece 6 engages with the helical grooves on the rod 8 through the medium of a tracer 24 (Figs. 5, 6 and 7) which, as the bracket is moved in one direction is maintained at a definite inclination so as to engage with one helical groove formed on the rod 8, and when the bracket reaches the end of its traverse the tracer 24 engages with a surface 25 on the end of the rod 8 which swings the tracer about its pivot, thereby enabling the same to engage with the second helical groove formed on the rod 8 and effect the movement of the bracket in a reverse direction.

It will be appreciated that if necessary, a slidale element corresponding in shape to the surface 25, may be moved axially along the rod 8 so as to limit the traverse of the bracket 7 and thereby limit the number of packets which are removed from the delivery end of the stacker.

The batches of packets removed from the stacker, are arranged in succession on the platforms 4 so that an oncoming batch of packets moves the leading batch through a flexible mouthpiece 26 into an outer carton which is inserted over the mouth 27 of the mouthpiece 26. Due to the action of a batch of packets passing between the flexible blades 27 of the mouthpiece 26, the blades are extended outwardly so as to bind against the inner walls of a carton inserted thereon and hold the carton firmly in position until the required number of batches of packets have been inserted into the carton whereupon the carton is removed by the operator.

When the dog 17 arrests the movement of the rod 8, the pinion 9 ceases to rotate and stops the rotational movement of the pinion 10. The pinion 10 is connected to the shaft 11 by a yieldingly controlled link 28 which

is adapted to engage with a tooth 29 secured to the shaft 11 of the pinion 10. The link 28 is held in contact with the tooth 29 by a spring 30 which is so designed that when the pinion 10 is arrested, the tooth 29 forces the link 28 upwardly against the influence of the spring 30 and permits the pinion 10 to slip relatively to the shaft 11.

The helical grooves formed on the rod 8 are preferably designed in such a manner that the speed of the pusher piece 6 is greater in that portion of its traverse which is located directly above the delivery end of the stacker, than it is over the platforms 4. In this manner time is allowed, whilst the pusher piece passes over the platforms 4 for the desired number of packets to be moved above the delivery end of the stacker, whereupon the speed of the pusher piece is increased so as to rapidly move the desired number of packets and permit the oncoming packets to move freely above the delivery end of the stacker. The sloping portions 5 of the platforms 4 are formed so as to enable the pusher piece to engage with the lowermost packet of the batch, prior to the same being brought flush with the platforms 4.

It will be appreciated that a series of pusher pieces might be mounted upon an endless conveyor continuously or intermittently moved in one direction across the path of a batch of packets located beyond the delivery end of the stacker so as to remove at intervals a predetermined number of packets therefrom. Further, automatic means could be provided to arrest the conveyor if the desired number of packets are not located in the path of a pusher piece or alternatively the conveyor could be arranged to move the pusher pieces continuously or intermittently in one direction across the path of a batch of packets located beyond the delivery end of the stacker and automatic means provided to trip one or more pusher pieces out of the path of the packets if the desired number of packets are not located in the path of the same. Further, when the reciprocated pusher piece hereinbefore described is arranged above the delivery end of a vertical stacker, the same may be arranged to move the packets in one direction only, for example, the pusher piece may be constructed so as to be deflected upwardly during its return stroke so as to ride over the top surface of the uppermost packet.

What I claim as my invention and desire to secure by Letters Patent is:

1. A device for use on a packing machine of the type wherein packets are automatically moved in succession through a vertical stacker which comprises in combination means operable automatically to remove the packets in batches from the stacker and deliver the batches alternately to opposite sides

thereof, and means operable automatically to detect whether each batch comprises a predetermined number of packets.

2. A device for use on a packing machine 5 of the type wherein packets are automatically moved in succession through a vertical stacker which comprises in combination means operable automatically to remove the packets in batches from the stacker and deliver the batches alternately to opposite sides thereof, and means operable automatically to ensure that each batch comprises a predetermined number of packets.

3. A device for use on a packing machine 15 of the type wherein packets are automatically moved in succession through a vertical stacker which comprises in combination means operable automatically to receive the packets in line and move the same through a 20 vertical stacker in superimposed relationship, means operable automatically to arrange the packets in batches and move the same in succession in a horizontal plane and means operable automatically to ensure that 25 each batch comprises a predetermined number of packets.

4. A device for use on a packing machine of the type wherein packets are automatically moved in succession through a vertical 30 stacker which comprises in combination a pusher piece operable automatically to remove packets in batches from the stacker and deliver the same alternately to opposite sides thereof, driving mechanism for said 35 pusher piece, means associated with the pusher piece operable automatically to detect whether each batch comprises a predetermined number of packets and adapted to arrest automatically the driving mechanism of said pusher piece until each batch comprises a predetermined number of packets.

5. A device for use on a packing machine of the type wherein packets are automatically moved in succession through a vertical 45 stacker which comprises in combination means operable to receive the packets in line and move the same through a vertical stacker in superimposed relationship, a pusher piece operable automatically to arrange the packets in batches and move the same in succession in a horizontal plane, driving mechanism for said pusher piece and means associated with the pusher piece and 50 operable automatically to arrest the driving mechanism of the pusher piece until each batch comprises a predetermined number of packets.

6. A device for use on a packing machine 55 of the type wherein packets are automatically moved in succession through a vertical

stacker which comprises a pusher piece, a rotatable diamond threaded rod arranged to reciprocate said pusher piece across the delivery end of the said stacker so as to deliver batches of packets alternately to opposite sides of the stacker and means associated with the pusher piece operable automatically to arrest the rotation of said rod until each batch comprises a predetermined number of packets.

7. A device for use on a packing machine 65 of the type wherein packets are automatically moved in succession through a vertical stacker which comprises in combination a pusher piece arranged to be reciprocated 75 across the delivery end of a stacker by a diamond threaded rod having the pitch of the thread increased at the mid-length thereof and adapted to deliver batches alternately to opposite sides of the stacker and means 80 associated with the pusher piece operable automatically to arrest the driving mechanism thereof until each batch comprises a predetermined number of packets.

8. A device for use on a packing machine 85 of the type referred to and as claimed in claim 4, wherein the pusher piece is arranged to be displaceable in a direction transverse to the path of the same across the delivery end of the stacker, so as to stop automatically the driving mechanism of the 90 pusher piece.

9. A device for use on a packing machine 95 of the type referred to and as claimed in claim 4, wherein the pusher piece is arranged to be displaceable in a direction transverse to the path of the same across the delivery end of the stacker, so as to stop automatically the driving mechanism of the pusher piece, and means operatively connected to the pusher piece and arranged to engage with the leading packet in the stacker 100 so as to restrict the displacement of the pusher piece in a direction transverse to the path of the same.

10. A device for use on a packing machine 105 of the type referred to, which comprises a pusher piece operable automatically to remove packets in batches from a stacker and deliver the batches alternately to opposite sides of the stacker, a driving mechanism for said pusher piece, said pusher piece being yieldingly mounted, on said driving mechanism so as to be displaceable in a direction transverse to the path of the pusher 110 piece.

In testimony whereof I hereunto affix my signature.

WALTER EVERETT MOLINS.
